DEAN A. EMERSON, OF DERBY, CONNECTICUT, ASSIGNOR TO THE STAR PIN COMPANY,
OF DERBY, CONNECTICUT.

DISPLAY CARTON.

Application filed April 8, 1926. Serial No. 100,629.

This invention relates to display cartons, and more particularly to a carton comprising a container and cover, and having means secured to the inner surface of the cover to 5 support the carton in an inclined position where the articles contained therein may be displayed to view.

It is customary in the sale of articles, particularly of small articles, to display them in 10 the cartons or containers in which they are packed for shipment. As the contents of the container may be more readily seen when the latter is held in an inclined position, it is desirable to have some means for supporting the containers in such position. It is contemplated in the present invention to provide hinged supporting members so secured upon the inner surface of the cover of the container that these supporting members may 15 be turned about their hinges to a vertical or upstanding position and there secured or locked so that the container or tray of the carton may rest against the inclined edges of these members and be supported in an inclined position.

One object of my invention, therefore, is the provision of a display carton having hinged members secured to the inner surface of the cover thereof, which members may be 20 secured in an upstanding position to support the container in an inclined position.

Another object of the invention is the provision of a display carton having supporting members secured to the inner surface of the 25 cover thereof, the supporting members consisting of a section secured to the inner surface of the container and a hinged section swingable about the secured section so as to be turned to an upstanding position, and 40 means for locking these members in such position to support the container or tray of the carton.

To these and other ends the invention consists in the novel features and combination 45 of parts to be hereinafter described and claimed.

In the accompanying drawings:

Fig. 1 is a perspective view of a carton embodying my invention in display or open position;

Fig. 2 is a perspective view of the cover thereof showing the supporting members or easel legs locked in upstanding position;

Fig. 3 is a plan view of the cover showing 50 one of the supporting members in inopera-

tive or folded position and the other in upstanding position;

Fig. 4 is a sectional view on line 4—4 of Fig. 3.

In order to illustrate a preferred embodiment of my invention, I have shown a display carton comprising a rectangular container or tray portion 10 within which the articles to be displayed are packed, and a cover 11. The display carton shown is a rectangular container of the usual form, and the cover 11 is designed to fit closely thereon so as to form a covered rectangular box or carton, which, when closed for shipment, for example, does not differ in appearance from 60 the usual rectangular container. The cover 11 is provided with the usual side flanges 12. Upon the inner surface of the cover is secured a pair of supporting members each comprising a section 13 secured flatwise to 65 the inner surface of the cover, and a section 14 hinged to the first named section about the weakened or hinged lines 15 and 16. As shown at the right in Fig. 3, when the cover is to be placed upon the box the section 14 70 may be folded downwardly against the inner surface of the cover so as to occupy no more space than the thickness of the section 14, which is practically negligible, so that the 75 cover will fit closely upon the container. 80

As also shown, more especially at the right in Fig. 3, the supporting member is cut through along the full lines 17, 18, 19 and 20, and is provided with a hinge or weakened line 21. With this construction, the only 85 connection between the hinged section 14 and the fixed section 13 of the supporting member is constituted by the lines 15 and 16, so that the section 14 may be readily swung about its hinges to occupy an upstanding position in a vertical plane, as shown at the 90 left of Fig. 3.

A hinged locking member 22 is provided by cutting entirely through the supporting member on the lines 18, 19 and 20, and by 100 providing the hinge line 21, this locking member or tongue being swingable about the hinge 21 into an upstanding position, as shown in Fig. 4, in a vertical plane substantially transverse to the plane of section 14 105 when the latter occupies an upstanding position. It will be apparent that, due to the shape of the cut 20 and its junction with the line 19, a recess 23 is formed to receive the lower edge of the section 14. In practice 110

the angular portion of the section 14 between the lines 17 and 18 will be received in this recess when the locking tongue 22 is in vertical position, so that there will be an interlocking engagement between the members, and thus any tendency of the tongue 22 to fall and release the supporting section 14 will be prevented.

The tongue 22 is provided partially from the material of the secured section 13 and partially from the hinged section 14, so that when the latter section is in upstanding position a part of the tongue member 22 will lie on either side thereof.

15 It will be noted that the supporting members consisting of the two sections 13 and 14 are separate elements secured to the inner surface of the container cover, so that this cover is not mutilated in any way. As these 20 supporting members will usually be formed of cardboard, for instance, they take up very little room within the cover and do not prevent the latter fitting closely upon the container itself.

25 The operation of the device will be more or less obvious from the foregoing description. In shipment the hinged sections 14 and the tongues 22 are folded flatly against the cover, which is placed upon the container 30 in the usual way. When it is desired to display the articles within the container the hinged sections 14 are turned into an upstanding position and the tongues 22 are thereupon swung to a vertical position, thus 35 locking the sections 14 in place. The container may then be supported upon the inclined edges 24 of the sections 14, the front edge of the container abutting against and being held against forward movement by the 40 side flange 12 upon the box cover. The tongues 22 may, of course, at any time be turned downwardly again to occupy a flat position against the cover and thus release the hinged sections 14 so that they may be folded 45 against the cover and the cover placed on the container in the usual way.

While I have shown and described a preferred embodiment of my invention, it will be understood that it is not to be limited to 50 all the details shown, but is capable of modification and variation within the spirit of the invention and within the scope of the appended claims.

What I claim is:

55 1. A display carton, comprising a container and a cover therefor, and supporting members secured to the inner surface of the cover, each of said supporting members comprising a section secured flatwise to the 60 inner surface of the container cover, and a section hingedly connected to the first named section and adapted to lie flatwise against the inner surface of the cover when the latter is on the container, and to be swung to an

upstanding position in a plane at right angles 65 to said surface of the container to support the latter to display the contents thereof, said hinged section having an inclined free edge on which the container is adapted to be supported in an inclined position, and means 70 for releasably securing said hinged sections in upstanding position, said securing means maintaining said sections in such upstanding position when the container is lifted therefrom. 75

2. A display carton, comprising a container and a cover therefor, and supporting members secured to the inner surface of the cover, each of said supporting members comprising a continuous section secured flatwise to the inner surface of the container cover, and a section hingedly connected to the first named section and adapted to lie flatwise against the inner surface of the cover when the latter is on the container, and to be swung to an upstanding position in a plane at right angles to said surface of the container to support the latter to display the contents thereof, said hinged section having an inclined free edge on which the container is adapted to be supported in an inclined position, and means for releasably securing said hinged sections in upstanding position, said securing means maintaining said sections in such upstanding position when the container is lifted therefrom, and said securing means comprising a tongue cut partially from the fixed section of the supporting member without breaking the continuity thereof. 90

3. A display carton, comprising a container and a cover therefor, and supporting members secured to the inner surface of the cover, each of said supporting members comprising a section secured flatwise to the inner surface of the container cover, and a section hingedly connected to the first named section and adapted to lie flatwise against the inner surface of the cover when the latter is on the container and to be swung to an upstanding position in a plane at right angles to said surface of the container to support the latter to display the contents thereof, said hinged section having an inclined free edge on which the container is adapted to be supported in an inclined position, and means for releasably securing said hinged sections in upstanding position, said securing means maintaining said sections in such upstanding position when the container is lifted therefrom, said cover having side flanges and said supporting members being disposed within the cover so that when the container is placed thereon the front edge thereof rests against one of said flanges. 110

In witness whereof, I have hereunto set my hand this 3rd day of April, 1926.

DEAN A. EMERSON.
